FIG.1

FIG.2

FIG.3

FIG.4

FIG.5

FIGURE 1 is a side elevational view of a knife showing my new design.

FIGURE 2 is a bottom view of the knife of FIGURE 1.

FIGURE 3 is a top plan view of the knife of FIG-
URE 1.

FIGURE 4 is a transverse sectional view upon the line
4—4 of FIGURE 1.

FIGURE 5 is a transverse sectional view upon the line
5—5 of FIGURE 1.

The characteristic features of my design reside in the table knife disclosed of the particular handle portion formed of plastic plaques having metallic bands on each side thereof connecting the end cap or piece with the integral blade supporting shank in combination with a relatively short blade forming a scalene obtuse triangle with the base thereof lying in the plane of the handle, all as shown.

I claim:

The ornamental design for a knife, as shown and described.
